UNITED STATES PATENT OFFICE.

JOHN F. O'CONNOR, OF CHICAGO, ILLINOIS, ASSIGNOR TO WILLIAM H. MINER, OF CHICAGO, ILLINOIS.

TWIN-ARRANGED FRICTION DRAFT-GEAR.

1,130,013.

Specification of Letters Patent.

Patented Mar. 2, 1915.

Application filed December 13, 1913. Serial No. 806,391.

To all whom it may concern:

Be it known that I, JOHN F. O'CONNOR, a citizen of the United States, residing in Chicago, in the county of Cook and State 5 of Illinois, have invented a new and useful Improvement in Twin-Arranged Friction Draft-Gears, of which the following is a specification.

This invention relates to improvements 10 in twin-arranged friction draft-gears.

One object of the invention is to provide a twin-arranged friction draft-gear having a preliminary compression spring and so constructed that the shocks under buff are 15 transmitted to the center sills at a plurality of points.

The invention furthermore consists in the improvements in the parts and devices and in the novel combinations of the parts and 20 devices herein shown, described or claimed.

In the drawing forming a part of this specification, Figure 1 is a part plan and part horizontal section of a draft-gear embodying my improvements. Fig. 2 is a 25 part side elevation, part vertical section taken on the line 2—2 of Fig. 1. Fig. 3 is a transverse vertical section taken on line 3—3 of Fig. 1, and Figs. 4 and 5 are detail perspective views of the two casings employed in my gear.

In said drawing the car center sills are designated by the reference 10, the same being slotted as at 11 and 12. Within the slots 11 are placed elongated stop castings 35 13 which are securely riveted to the sills and which are provided with outwardly extended flanges 14 slotted so as to provide two keyways 15 and 16. Also secured to the center sills 10 are the upper and lower 40 front stops 17, the latter being slotted in alignment with the slots 12 to receive therethrough a coupler and yoke-connecting key 18. The key 18 passes through a suitable slot in the butt end of the draw-bar 19 and 45 through elongated slots 20 in draft links 21. At their rear ends, the links 21 are slotted to receive the transversely extending key 22 which moves with the links and form therewith a yoke operating in the ordinary 50 manner. Intermediate the keys 18 and 22 and operable in the slots 16 is another transversely extending key 23 which also passes through elongated slots 24 in the links 21. Between the links 21 and in engagement 55 with the inner end of the coupler is a front,

vertically elongated follower 25 recessed on each side, as at 26, to fit over the links 21. To the rear of the front follower and between the links 21, are two casings 27 and 28, the former being herein referred to as 60 the main casing and the latter as the auxiliary casing. The main casing 27 is provided with two main spring pockets 128 arranged in parallel one above the other and in which are seated nested sets of main 65 springs 29. In alignment with each spring pocket 128 and formed integral with the casing 27 is a friction shell 30, in each of which shells is mounted and coöperable therewith, a set of friction elements comprising friction shoes 31 and spreader or wedge 32, the latter being in engagement with the rear side of the front follower 25. To hold the parts properly assembled and to provide a certain amount of initial compression on the main springs, through bolts 33 are provided which extend through the rear wall 34 of the main casing and through the front follower, as indicated most clearly in Fig. 2. To the rear of the back wall 34, the casing 27 is provided with cylindrical spring pockets 35 arranged in alignment with the main spring pockets 28. The casing 28 is provided with cylindrical portions 36 which telescope over the parts 35 of the main casing and between the rear wall 34 of the main casing and the back wall 37 of the auxiliary casing are placed two sets of nested preliminary compression springs 38 which normally separate the casings to the extent indicated in Fig. 2. The casing 28, on each side thereof, is provided with forwardly extended arms 39 which slide and operate in correspondingly located and shaped grooves 40 on the sides of 90 the main casing 27. The arms 39 are slotted, as indicated at 41, to receive the key 22, said key also passing through a correspondingly located slot 42 in the central portion of the casing 27, it being understood that the slots 41 and 42 are all longer than the width of the key 22. The main casing 27 is also provided with another slot 43 adapted to receive the key 23.

The operation is as follows: Under buff, 105 the draw-bar will force the follower 25 backwardly, which in turn will move the main casing 27 with the friction mechanism therein and compress the preliminary compression springs 38, the end of 28 being held 110

- from rearward movement by the key 22. After the preliminary compression springs have been compressed the main casing 27 will be brought to rest, since it will engage 5 with the casing 28 telescoped therewith and the key 23 will come into engagement with the rear ends of the slots 16 in the stop castings. In this way the heavy shocks under buff are distributed to the castings at four 10 different points and the strain on the rear key 22 is thereby relieved and the shocks more evenly transmitted to the center sills. Continued rearward movement brings the friction mechanisms into action. Under 15 pull, the links 21 with the key 22 will be moved forwardly, which in turn will move the casing 28 to compress the preliminary compression springs 38, movement of the main casing 27 being prevented on account 20 of the greater resistance to movement due to the friction mechanisms contained therein. When the two casings 27 and 28 have been completely telescoped a continued forward movement of the links 21 and key 22 will 25 move the casing 27 and bring the friction mechanisms into operation and the parts brought to rest when the casing 27 abuts the front follower 25 and the key 23 engages the front ends of the slots 16. The intermediate 30 key 23 supports the main casing 27 and permits the removal at any time of the smaller casing 28 and the preliminary compression springs 38 for repairs or renewal of the compression springs.
- 35 From the preceding description it will be seen that I have provided a friction draft gear of high capacity in which two complete sets of friction mechanisms and preliminary compression springs are employed and 40 which are arranged in parallel one above the other. The construction is also such that the severe buffing shocks are transmitted to the center sills at four different points.
- Although I have herein shown and de- 45 scribed what I now consider the preferred embodiment of my improvements, yet it will be understood that various changes and modifications may be made without departing from the spirit of the invention, and all 50 such changes and modifications are contemplated as come within the scope of the claims appended hereto.
- I claim:
1. In a railway draft gear, two members relatively longitudinally movable, one of 55 said members having two sets of twin-
- arranged main springs and friction mechanisms, a preliminary compression spring between said members, and means for transmitting the shocks under buff, separately 60 from each of said members to the center sills, said means including two horizontally extending keys passing through said members and slidably in slots in the center sills, substantially as specified. 65
2. In a railway draft gear, a draw-bar; a yoke, the latter including a transversely extended key; two casings relatively longitudinally movable and having preliminary compression springs therebetween, said key 70 slidably engaging both of said casings, one of said casings having sets of twin-arranged main springs and friction mechanisms therewithin; and a second key extended through the casing having the friction mechanisms 75 therein and adapted to support the same, substantially as specified.
3. In a railway draft-gear, in combination: two casings telescoped with respect to each other and relatively longitudinally 80 movable; twin-arranged sets of main springs and friction mechanisms within one of said casings; preliminary compression springs interposed between said casings in twin arrangement and in alinement with the friction mechanisms; a key extended through slots in both of said casings to thereby connect the same; links connecting said key with the draw-bar; and a second key passing through said casing having the friction 85 mechanisms therein and through slots in said links and adapted to support the casing, substantially as specified.
4. In a railway draft gear, two members relatively longitudinally movable, one of 90 said members being provided with main springs and friction mechanism therewithin, a preliminary compression spring between said members, and two keys, one of said keys extending through slots in both of said members to thereby slidably connect the same together and the other of said keys passing through the member provided with the main 95 springs and friction mechanism and adapted to support the same. 100
- Signed this 9th day of December, 1913, in the presence of two witnesses.
- JOHN F. O'CONNOR.
